[57] CLAIM

The ornamental design for a container for segregating waste materials, as shown and described.

DESCRIPTION

FIG. 1 is a front perspective view of a container for segregating waste materials showing our new design;
FIG. 2 is a front elevational view thereof;
FIG. 3 is a rear elevational view thereof;
FIG. 4 is a right side elevational view thereof, the left side view being identical;
FIG. 5 is a top plan view thereof;
FIG. 6 is a bottom plan view thereof;
FIG. 7 is a front perspective view of a second embodiment of the container for segregating waste materials;
FIG. 8 is a front elevational view of FIG. 7;
FIG. 9 is a rear elevational view of FIG. 7;
FIG. 10 is a right side elevational view of FIG. 7, the left side view being identical;
FIG. 11 is a top plan view of FIG. 7;
FIG. 12 is a bottom plan view of FIG. 7;
FIG. 13 is a front perspective view of FIG. 1 in partial unassembled condition;
FIG. 14 is a front elevational view of FIG. 13;
FIG. 15 is a rear elevational view of FIG. 13;
FIG. 16 is a right side elevational view of FIG. 13, the left side view being identical;
FIG. 17 is a top plan view of FIG. 13; and,
FIG. 18 is a bottom plan view of FIG. 13.
